CORE COVERING APPARATUS

Axel C. Nystrom, Rutherford, N. J., assignor to
 Western Electric Company, Incorporated, New
 York, N. Y., a corporation of New York

Application October 7, 1942, Serial No. 461,225

16 Claims. (Cl. 57—15)

This invention relates to core covering apparatus, and more particularly to tape serving machines.

In tape serving machines the supply pads of tape are usually mounted in a serving head rotatable about an advancing strand to which the tape is served. The speed at which the machine may be operated in serving the tape depends greatly upon control of the tension on the tape. In most instances the tape is drawn from its supply, causing rotation of the supply upon a suitable shaft. However, although frictionless bearings may be provided to minimize the drag at the supply, an increase in speed of the serving head increases the drag due to the increase in centrifugal force. It has been found advantageous, therefore, to eliminate the effect of centrifugal force on such supply pads so that the speed of the serving head may be increased without increasing the tension on the tape being served.

An object of the invention is to provide a material serving apparatus, and more particularly a simple yet highly efficient serving head for serving material to an advancing core.

With this and other objects in view, the invention comprises a serving head rotatable about an advancing core and having a spindle to rotatably support a supply of material adapted to be served to the core, with means adapted to rotate the spindle in the direction of rotation of the supply to remove any drag on the supply due to centrifugal force.

Other objects and advantages will be apparent from the following detailed description when considered in conjunction with the accompanying drawings, wherein

Fig. 1 is a front elevational view of the machine, portions thereof being shown in section;

Fig. 2 is a fragmentary top plan view of the structure shown in Fig. 1, portions thereof being broken away, and

Fig. 3 is a vertical sectional view taken along the line 3—3 of Fig. 1.

Referring now to the drawings, attention is first directed to Fig. 1, which illustrates a frame 10 upon which uprights 11 and 12 are mounted. The upper end of the upright 11 has a bearing portion 14 to rotatably support a hollow shaft 15. A multiple pulley 16 is mounted upon the shaft 15 and is operatively connected to a driving motor 17 through the aid of belts 18 and a multiple pulley 19. The inner portion of the shaft 15 has a sun gear 20 and a flange 21 mounted thereon, the latter being fixed to an end 22 of a

5 serving head indicated generally at 23. An end 24 of the serving head is supported by a flange member 25 which is mounted upon a hollow spindle 26, the latter being supported by the upright 12. Lateral beams 20, of the serving head shown in Figs. 1 and 3, are disposed at diametrically opposed positions between the ends 22 and 24 and are supported thereby. These beams are identical in structure and so is the material or 10 tape supplying means carried thereby. Therefore, a specific description of one tape supply will serve for both supplies shown.

Attention is, therefore, directed to the lower portion of the serving head shown in Fig. 1. 15 Here an aperture 31 is formed in the beam 30 in such a manner as to support a frictionless bearing 32 held in place by a cover plate 33. The bearing 32 rotatably supports a spindle 34 which projects inwardly toward the center of the head 23, where another frictionless bearing 36 rotatably supports a tape holder 37. The tape holder is of the structure shown, being circular in general contour with a hub portion 38, upon which a pad 39 of tape 40 is disposed, and a disc-shaped portion 41 to support the pad by centrifugal force. 20 The inner end of the hub portion 38 is closed, as at 42, to rest upon the inner end of the spindle 34. A ring gear 44, of the worm type, is disposed concentric with the spindle 34 and secured to 25 the pad holder 37 by means of screws 45. This gear is operatively connected to a brake means hereinafter described, to impart a given braking force on the holder to create a predetermined tension in the tape being served. A worm gear 48 is fixedly mounted upon the spindle 34 and interengages a worm 49.

Considering first the spindle driving means, attention is again directed to the sun gear 20, which has planet gears 52 and 53 disposed in interengagement therewith and to be driven thereby during the rotation of the serving head 23. The planet gear 53 is fixedly mounted upon a shaft 54, which is journaled in suitable bearings and supports the worm 49. The planet gear 53 is fixedly mounted upon a shaft 55, which is suitably journaled in bearings and has a worm 56 identical with the worm 49 mounted thereon and disposed in interengagement with its worm gear 48. It will be apparent, by viewing Figs. 1 and 3, that the worms 49 and 56 are positioned upon opposite sides of their respective worm gear 48, the purpose of this structure being to cause rotation of their spindle 34 in opposite directions from the direction of rotation of their respective pad holder 37.

Attention is now directed to the brake applying means. The hollow shaft 15 has a tubular member 60 slidable axially therein and normally urged outwardly, that is to the left, by the force of a spring 61 which may be varied through the adjustment of a nut 62, the latter being threadedly mounted upon the outer end of the tubular member. The tubular member projects through the shaft 15 and into the serving head 23 to a position where a bracket 64 is mounted and provided with pairs of guide rolls 66, over which the tapes 40 from the pads 39 may pass in being directed to an advancing core 67. The core 67 passes through the tubular member 60, a polishing head 68 and the hollow spindle 26. The polishing head is supported a desired distance from the outlet end of the tubular member 60, or the guide rolls 66, through the aid of parallel rods 69 shown in Fig. 2. Thus there are provided guide rolls 66 to receive the tapes from their supply pads and direct the tapes for spiral windings in like directions on the core during the advancement of the latter.

A brake unit 70, which is of the multiple disc type, is under the control of the spring 61 and the tapes to serve in maintaining constant tension on the tapes. It is believed that a detailed structure of this brake is not necessary for a clear understanding of the invention, as multiple disc brakes are well known in the art. However, worm gears 71 and 72 are rotatably mounted upon the tubular member 60 and have the discs of the brake 70 disposed therebetween, certain of the discs being connected for rotation with the gear 71 while the intermediate discs are connected for rotation with the gear 72. These gears are caused to rotate in opposite directions and the friction existing between the discs of the brake 70 creates a braking force between the gears. A disc-shaped member 74 is disposed concentric with the tubular member 60 but held against axial movement with respect to the member by the aid of the end 22 of the serving head. A head member 75, fixed to the tubular member 60, is movable therewith under the force of the spring 61, to normally urge the gear 72 toward the gear 71 and create a predetermined braking force in the brake unit 70 depending upon the force of the spring 61. The braking force existing at the gears 71 and 72 is transmitted to their respective pad holder 37 through worms 78 and 79 respectively. These worms have universal connections 80 with their respective shafts 81 and 82, to drive worms 83 and 84 respectively (Fig. 3) to in turn drive their respective gears 44. Therefore, during the rotation of the pads 39 resulting from the paying off of the tapes 40, the pad holders will be rotated in opposite directions, rotating their gears 44 accordingly to eventually rotate the worm gears 71 and 72 in opposite directions. The braking force existing between the gears 71 and 72 will then be transmitted back through their driving connections to the supply pads, to create a given drag upon each tape and create a given tension therein. As the braking force originates between the two gears 71 and 72, the tension upon the tapes will be equal.

Upon considering the operation of the apparatus, let it be assumed that the core 67, which in the present instance may be a strand or cable structure, is advanced at a given speed through the serving head. After the ends of the tape 40 have been attached to the core prior to the starting of the advancing movement thereof, the

serving head may be caused to rotate through the energization of the motor 17. Thus the serving head is rotated in a given direction, namely clockwise (Fig. 3), and during this rotation the tape is paid off of the supply pads about their respective guide rolls 66 and served to the core in reverse spiral wrappings. At the beginning of the rotation of the serving head, a given tension is applied to the tapes through the brake unit 70 affected by the force of the spring 61, which braking force is transmitted through the worms 78 and 79, their shafts 81 and 82, the worms 83 and 84, to their gears 44.

As the speed of the serving head increases, centrifugal force would create another braking force at the spindles 34 if the spindles remained stationary. However, the spindles are driven not only in the direction of rotation of their respective pads and pad holders but at speeds in excess of the speeds of their pads and pad holders. This driving means is taken from the sun gear 28 through the planet gears 52 and 53, their respective shafts 54 and 55, to the gears 48, through their worms 49 and 56. Thus the spindles 34 from the beginning of the rotation of the serving head to the maximum speed of rotation of the latter, rotate the spindles in advance of their pad holders, creating an assisting driving force for the pad holders and removing frictional drag which would exist if the spindles were allowed to remain against rotation. The driving force of the spindles may tend to decrease the tension on the tapes 40, but this is compensated for by the brake unit 70 and its assisting spring 61. Therefore, there exists an overlapping of effort between the tension means at the brake unit 70 and the driving means at the spindle, to eliminate any undue tension on the tape, particularly during the starting of the serving head. It is, therefore, apparent that regardless of the speed of the head and the centrifugal torque on the pad holders, the tension on the tapes may be maintained constant.

Although specific improvements of the invention have been shown and described, it will be understood that they are but illustrative and that various modifications may be made therein without departing from the scope and spirit of this invention as defined by the appended claims.

50 What is claimed is:

1. A material serving apparatus comprising a serving head rotatable about an advancing core and including a holder, for a supply of material to be served to the advancing core, rotated about an axis at an angle with respect to the axis of the serving head and in a given direction by the material being withdrawn from the supply, a spindle to support the holder for rotation, and means to rotate the spindle in the said given direction.

2. A material serving apparatus comprising a serving head rotatable about an advancing core and including a holder, for a supply of material to be served to the advancing core, rotated in a given direction by the material being withdrawn from the supply, a spindle to support the holder for rotation, and means to rotate the spindle in the said given direction and at a speed greater than that of the holder.

70 3. A material serving apparatus comprising a serving head rotatable about an advancing core and including a holder, for a supply of material to be served to the advancing core, rotated in a given direction by the material being withdrawn from the supply, means to rotatably support the

holder, means to create a given tension on the material being served, the holder being affected by centrifugal force during its rotation with the serving head tending to move the holder relative to its supporting means to create a drag on the material being served, and means adapted to cause the holder to remove the drag from the material.

4. A material serving apparatus comprising a serving head rotatable about an advancing core and including a holder, for a supply of material to be served to the advancing core, rotated in a given direction by the material being withdrawn from the supply, means to rotatably support the holder, means to create a given tension on the material being served, the holder being affected by centrifugal force during its rotation with the serving head tending to move the holder relative to its supporting means to create a drag on the material being served, and means tending to rotate the holder to remove the drag from the material.

5. A material serving apparatus comprising a serving head rotatable about an advancing core and including a holder, for a supply of material to be served to the advancing core, rotated in a given direction by the material being withdrawn from the supply, means to rotatably support the holder, means to create a given tension on the material being served, the holder being affected by centrifugal force during its rotation with the serving head tending to move the holder relative to its supporting means to create a drag on the material being served, and means to rotate the supporting means with the holder to remove the drag from the material.

6. A material serving apparatus comprising a serving head rotatable about an advancing core and including a holder, for a supply of material to be served to the advancing core, rotated in a given direction by the material being withdrawn from the supply, means to rotatably support the holder, means to create a given tension on the material being served, the holder being affected by centrifugal force during its rotation with the serving head tending to move the holder relative to its supporting means to create a drag on the material being served, and means to rotate the supporting means with and at a faster speed than the holder to remove the drag from the material.

7. A material serving apparatus comprising a serving head rotatable about an advancing core and including a holder, for a supply of material to be served to the advancing core, rotated in a given direction by the material being withdrawn from the supply, means to apply a given braking drag on the holder to create a given tension in the material, the holder being affected by centrifugal force during its rotation with the serving head to create an additional drag on the material, and means adapted to cause the holder to remove the said additional drag.

8. A material serving apparatus comprising a serving head rotatable about an advancing core and including a holder, for a supply of material to be served to the advancing core, rotated in a given direction by the material being withdrawn from the supply, means to apply a given braking drag on the holder to create a given tension in the material, the holder being affected by varying centrifugal forces during varying rotary speeds of the serving head to create an additional drag of varying values on the material, and operable

means variable with the said varying forces to remove the said additional drag.

9. A material serving apparatus comprising a serving head rotatable about an advancing core and including a holder, for a supply of material to be served to the advancing core, rotated in a given direction by the material being withdrawn from the supply, means to apply a given braking drag on the holder to create a given tension in the material, the holder being affected by varying centrifugal forces during varying rotary speeds of the serving head to create an additional drag of varying values on the material, and means operable at variable speeds with the serving head to cause removal of the said additional drag.

10. A material serving apparatus comprising a serving head rotatable about an advancing core and including a holder, for a supply of material to be served to the advancing core, rotated in a given direction by the material being withdrawn from the supply, a spindle to support the holder for rotation, means to apply a given braking drag on the holder to create a given tension in the material, the holder being affected by centrifugal force during its rotation with the serving head to create an additional drag on the material, and means to rotate the spindle to remove the said additional drag on the material.

11. A material serving apparatus comprising a serving head rotatable about an advancing core and including a holder, for a supply of material to be served to the advancing core, rotated in a given direction by the material being withdrawn from the supply, a spindle to support the holder for rotation, means to apply a given braking drag on the holder to create a given tension in the material, the holder being affected by centrifugal force during its rotation with the serving head to create an additional drag on the material, and means to rotate the spindle with and at a faster speed than the holder to remove the said additional drag on the material.

12. A material serving apparatus comprising a serving head rotatable about an advancing core and including a holder, for a supply of material to be served to the advancing core, mounted parallel with the axis of the head for rotation in a given direction by the material being withdrawn from the supply, means to apply a given braking drag on the holder to create a given tension in the material, the holder being affected by centrifugal force during its rotation with the serving head to create an additional drag on the material, and means adapted to cause the holder to remove the said additional drag.

13. A material serving apparatus comprising a serving head rotatable about an advancing core and including a plurality of holders, for supplies of materials to be served to the advancing core, rotated about axes at angles with respect to the axis of the serving head by the materials being withdrawn from the supplies, spindles to support the holders for rotation, and means to rotate each spindle in the direction of its holder.

14. A material serving apparatus comprising a serving head rotatable about an advancing core and including diametrically opposed holders, for supplies of materials to be served to the advancing core, rotated about axes at angles with respect to the axis of the serving head and in opposite directions by the materials being withdrawn from the supplies, spindles to support the holders for rotation, and means to rotate each spindle in the direction of its holder.

15. A material serving apparatus comprising a

serving head rotatable about an advancing core and including diametrically opposed holders for supplies of materials to be served to the advancing core, rotated in opposite directions by the materials being withdrawn from the supplies, brake means driven by the holders to cause application of given tensions to the materials, the holders being effected by centrifugal force during their rotation with the head to create additional tension on the materials, and means adapted to cause the holders to remove the said additional tensions.

16. A material serving apparatus comprising a serving head rotatable about an advancing core,

a holder for a supply of material to be served to the advancing core, a spindle to support the holder for rotation about an axis disposed at right angles with respect to the advancing core, means to apply a given brake drag on the holder to create a given tension in the material, the holder being affected by centrifugal force during its rotation with the serving head to create an additional drag on the material, and means to rotate the spindle in the direction of rotation of the holder and at a faster speed than the holder to remove the said additional drag on the material.

AXEL C. NYSTROM.
